UNITED STATES PATENT OFFICE.

ADALBERT BESTA, OF DUISBURG, GERMANY, ASSIGNOR TO CHEMISCH-TECHNISCHE GESELLSCHAFT MIT BESCHRANKTER HAFTUNG, OF DUISBURG, GERMANY.

CIRCULATING APPARATUS FOR HOT GASES.

Application filed February 10, 1928, Serial No. 253,511, and in Germany February 18, 1927.

The heating of heaters of the most varied kinds, glow retorts for example, by means of heating gases passing round a circuit, is the more economical the shorter the paths 5 taken by the heating gases. It is therefore particularly advantageous if the fan effecting the circulation of the hot gases is connected as near as possible to the heater appliance. Hitherto the heating burner has 10 had to be interposed between the heater and the fan that circulates the heating gas, so that longer paths for the heating gas were thereby rendered necessary. By the present invention this disadvantage is obviated and 15 the entire arrangement simplified by a particularly advantageous constructional form of circulating fan and heating appliance.

The invention consists in arranging the burner appliance for heating the circulating gases in or on the casing of the heating-gas circulating fan, so as to make the paths 20 of the heating gas as short as possible. The burner tube for the undisturbed burning of the necessary hot supplementary gases may 25 be so arranged that the circulating gases flow round about it. By arranging a throttling device for the circulating gases 30 in front of the entrance for the heating gases into the current of circulating gas, the flow 35 of the circulating gas can be regulated, so that the strength of the draught in the burner tube can be adjusted as desired, and the necessary quantities of gas and air can be sucked in by the heating burner itself.

The discharging of the excess gases from 40 the heating gas circulating system may advantageously be effected at the casing of the heating-gas circulating fan in such a way that a heating of the excess gases by 45 the burner appliance is obviated. The sensible heat of the excess gases may be utilized 50 for preheating the quantities of gas and air which are supplied to the heating burner.

The accompanying drawing shows one 45 constructional example of the invention. The retorts 1 in the heater appliance 2 are scoured and heated by heating gases flowing in the direction of the arrows. The heating gases are supplied through a pipe 50 union 3 to a circulating fan 4. At the lower part of the circulating fan 4 is arranged a burner appliance 5, consisting of a burner 6 and a burner tube 7. The heating gases flow round about the burner tube 55 7, are already preheated by the radiant

heat, and mix in the passage 8 with the heating-up gases of the burner. From the passage 8 the hot gases, heated to the desired temperature, are again passed in the direction of the arrows round the retorts 60 1 to the tube 3. At the end of the burner tube 7 are arranged throttling elements 9, which throttle the circulating gases, so that in the passage 8, and accordingly also in the burner tube 7, an optional 65 draught effect can be adjusted. The excess hot gases are led away through a tube 10 arranged on the upper fan casing, and pass through a double-walled tube 11 into the open. The hot superheated gases are then 70 led off through the central portion of the double walled tube 11 whilst air is led in through the outer annular portion and in the reverse direction to the outflowing super heated gases. This air becomes heated by 75 the hot walls of the inner tube and is fed to the burner through the tube 12. The supply of gas to the burner is effected through the pipe 13. For the accurate adjustment of the quantities of air and gas 80 for the burner 6, regulating elements 14 and 15 are arranged in the pipes 12 and 13.

What I claim is:—

1. Circulating apparatus for hot gases, comprising a substantially closed circuit in 85 which the hot gases circulate, a fan casing forming part of said circuit, a fan in said casing for circulating the hot gases, and a burner appliance arranged in the diffuser space of the said fan casing for heating up 90 the circulating gases, and a throttling device arranged in the circuit before the point at which the products of combustion from the burner appliance enter the circuit, for regulating the flow of the circulating gases. 95

2. Circulating apparatus for hot gases, comprising a fan casing, a fan in said casing for heating up the circulating gases, 100 and means for discharging from the fan casing and excess hot gases at a point prior to that at which the heating-up action of the burner appliance occurs.

3. Circulating apparatus for hot gases, 105 comprising a substantially closed circuit in which the hot gases circulate, a fan casing, forming part of said circuit, a fan in said casing for circulating the hot gases, and a burner appliance arranged in said fan cas- 110

ing for heating up the circulating gases, a at a point prior to that at which the heating-up action of the burner appliance occurs.
throttling device arranged in the circuit before the point at which the products of combustion from the burner appliance enter
5 the circuit, for regulating the flow of the circulating gases, and means for discharging from the fan casing the excess hot gases

In testimony whereof I have signed my name to this specification.

ADALBERT BESTA.
